UNITED STATES PATENT OFFICE.

PATRICK H. McCUALEY, OF DES MOINES, IOWA.

APPARATUS FOR HOISTING AND CONVEYING EARTH FROM SEWER-TRENCHES.

SPECIFICATION forming part of Letters Patent No. 280,645, dated July 3, 1883.

Application filed May 15, 1883. (No model.)

To all whom it may concern:

Be it known that I, PATRICK H. McCUALEY, of Des Moines, in the county of Polk and State of Iowa, have invented an Apparatus for Hoisting and Conveying Earth from Sewer-Trenches, of which the following is a specification.

My object is to save time, labor, and expense in making excavations for sewers and removing ground away on wagons; and my invention consists in the manner of forming and combining a portable elevated railway-track and car-dumping device adapted to be placed across a trench and under a portable derrick, as hereinafter fully set forth, in such a manner that a person on the elevated track can readily direct a bucket that is raised and lowered in the trench by horse-power to convey dirt from the bottom of the trench into a car on the track, and also move the car and dump its contents into a wagon aside of the trench.

Figure 1 of my accompanying drawings is a perspective view of my apparatus in position as required for practical use. Fig. 2 is a sectional view, showing a truck on the elevated track in position to receive the contents from a bucket suspended over it by means of the derrick and tackling. Fig. 3 is an enlarged 30 detail view and longitudinal section of the elevated track and dump combined therewith. Fig. 4 is a top view of Fig. 3. Fig. 5 is a transverse section of the track and dump. Jointly considered, these figures clearly illustrate the construction, application, and operation of my complete invention.

a a are the parallel rails of my elevated portable track. They are preferably made of hard wood covered with iron plates *b*, connected by means of cross-pieces *c*, and supported upon frames *d*, that are rigidly fixed to their ends by means of bolts, or in any suitable way, in such a manner as to adapt the complete elevated track to be placed across a trench, as clearly shown in Figs. 1 and 2.

a' are planks fixed on the outside of and parallel with the rails *a* to form walks for the operator.

a'' are the side pieces of the dump-frame, rigidly fixed against the outsides and ends of the rails *a*.

f is a section of track pivoted between the

pieces *a''* by means of a rod, *g*. *b'* are metal plates fixed on top of the pivoted track-rails. They extend beyond and terminate in upward 55 wheel-supports *b''*.

h are bridles pivoted to the suspended track-section *f* by means of a rod, *i*, that extends through the side pieces, *f''*, and connected with the inside faces and ends of the track-rails *a* 60 by means of bolts *k*, in such a manner that the tilting motion of the pivoted track-section *f* will be restricted by the bridles, as indicated by dotted lines in Fig. 3.

m represents a four-wheeled truck adapted 65 to be operated upon the elevated track.

Numbers 1 2 3 are the legs of a tripod or derrick, pivoted together at their top ends in such a manner that they can be folded into parallel positions relative to each other when not in 70 use, and readily spread apart at their lower ends, to be set astride of a trench and over my elevated track.

n represents a bucket having a hinged bottom, suspended from the top of the derrick by 75 means of pulleys and a rope in such a manner that it can be readily raised and lowered in the trench.

r is a rope-directing pulley attached to the lower end of one of the legs of the derrick. 80 By passing the rope over this pulley and hitching a horse to its free end the bucket can be easily raised, when filled with ground, by the movements of the horse along the side of the trench. When a loaded bucket is thus elevated above the track, the operator can move the truck *m* under it and unlatch its hinged bottom, and allow the contents to drop into the box of the truck, and then move the truck over the elevated track and upon the pivoted 90 section and dump *f* to engage the wheel-supports *b''*. By then lifting on the front end of the truck-box sufficiently to disturb its balance the pivoted section will be tilted and the rear and open end of the truck will descend 95 sufficiently to allow the contents of the box to drop into a wagon placed underneath, as clearly shown in Fig. 1. The operator upon one of the plank walks of the elevated track can then depress the front end of the truck 100 and move it in position to be filled again, and by so doing the pivoted section and dump will be readjusted as required to receive the loaded truck again. Clay, sand, earth, and rock, or

any material excavated from the trench, can thus be readily hoisted and placed upon a wagon to be carried away or dumped on the surface at either side of a trench to be in a 5 convenient position for filling it into the trench again, and much of the time, labor, and cost of shoveling dirt in building sewers dispensed with.

The complete portable apparatus can be 10 readily advanced from one point to another as the excavation of the trench progresses.

I claim as my invention—

1. The portable elevated-railway-track and dump, composed of the rails *a b*, cross-pieces *c*, frame *d d*, hinged track-section *f*, having 15 wheel-supports *b' b''*, the pivoted bridles *h*,

and pins or bolts *i*, substantially as shown and described, to operate in the manner set forth, for the purposes specified.

2. The hoisting and conveying apparatus, 20 composed of the portable elevated railway-track *a b a' a''*, the pivoted track-section and dump *f*, having wheel-supports *b''*, and hinged bridles *h*, the derrick consisting of three legs pivoted together at their top ends, a suspended bucket having a hinged bottom, and a truck, *m*, substantially as shown and described.

PATRICK H. McCUALEY.
